UNITED STATES PATENT OFFICE.

EMILE AUGUSTIN BARBET, OF PARIS, FRANCE.

CONTINUOUS RECTIFICATION OF LIQUIDS AT HIGH BOILING POINT.

Application filed June 11, 1923, Serial No. 644,774, and in France December 11, 1922.

This invention relates to the continuous rectification of hydrocarbons and other liquids containing constituents of high boiling point.

5 In performing the continuous rectification of hydrous alcohol no difficulties are encountered in producing an intensive ebullition in the base of the apparatus, and thereby obtaining at the upper part of the rectifier plates an abundance of reflux (retrogradation) liquid for refining the alcoholic vapours.

10

In the treatment of hydrocarbon and other liquids of high boiling point, such as heavy benzenes, petroleum and the like, difficulties are experienced in securing this result. It is, however, in the treatment of such liquids highly desirable to employ rectification as by the passage of bubbles of vapour through the reflux in a plate column a much sharper fractionation can be secured than by mere condensation.

According to the invention these difficulties are overcome by supplying the rectification apparatus with the material in the form of vapour instead of in the form of liquid and for this purpose the rectification apparatus employed is combined with a vaporizer in which the initial material is completely or as far as possible vaporized in two stages by the employment of saturated steam in the first stage and of superheated steam in the second stage.

It is known to combine distillation apparatus with vaporizers but in the known cases this is done only in connection with distilling as distinguished from rectifying apparatus, that is to say an apparatus in which the fractionation is effected not by rectification but merely by condensation. In rectification apparatus such evaporators are not employed.

It is desirable to push the rectification to such a degree that fractions having a high degree of homogeneity, such as a rectifying column alone is capable of producing, are obtained. As a matter of fact, only a plate column working upon previously condensed refluxes, is capable of effecting an accurate separation of the components, and thus produce relatively light oils (spindle oils), medium oils (machinery oils), and heavy oils (valvoline) for lubrication at very high temperatures.

55 Apparatus for achieving the above-stated

objects in illustrated in the accompanying drawing.

A separate column might be provided for the continuous treatment of the oils, but the apparatus shown in the drawing comprises only one plate column for effecting the extraction of the lighting oils in its upper part, and for effecting the fractionation of the three classes of oil in its lower part. 60

Only the initial vaporizer M must not be relied upon for vaporizing lubricating oils. For this purpose a much hotter steam is required, namely, superheated steam.

In general superheated steam is not an advantageous means for heating to high temperatures with the interposition of a heating surface, because it is nothing more nor less than a gas, and gases have small specific heat and a bad coefficient of heat transmission to heating surfaces. 75

But in the present case, on the one hand the specific heat of water vapour is more advantageous than that of air, and on the other hand the liquids to be heated and vaporized have very low coefficients of specific heat and latent heat of vaporization. Moreover, in the case of a raw petroleum of the American type, the preliminary extraction of the petrols (gasolines) and lighting oils has already reduced the liquid to about 30% of its initial volume. All these circumstances render the use of superheated steam quite effective.

In view of the foregoing, the working of the apparatus shown in the drawing will be readily understood. 90

Instead of the petrol (gasoline) vapour and the non-vapourized products being sent all together into the rectifying column, the liquid and the vapour are carefully separated. Only the vapour enters the column at N. 95

The liquid oils kept back by the separating flask O descend by way of a siphon-pipe into the second vaporizer M which is heated by highly superheated steam. This second vaporizer is very carefully insulated against heat-loss. 100

The mixture of vaporized oils and oils that are refractory to vaporization passes into the lower part of the rectifying column at a short distance from the base. The vapours ascend through the plates of the column and become rectified therein by bubbling-up through the refluxes of the upper 110

plates. The three cocks P^1 P^2 and P^3 draw off respectively the above-referred to three qualities of oils in the liquid state, whilst the lighting oils pass out as before through 5 the cocks P^4 and P^5 .

All these extractions pass into cooling worms and enter sheet-metal containers under vacuum.

The circulation of the superheated steam 10 in the second vaporizer must be assured. For this purpose a rotary exhauster Q is employed which draws the steam from the lower part of the second vaporizer M and forces it to flow in the steam superheater R 15 and then to enter again the upper part of the second vaporizer M , thus circulating in a continuous cycle.

To recapitulate, the rectification of the heavy oils is effected exactly on the same 20 principle as the rectification of the lighting oils, but with the use of a suitable source of heat, that is to say, steam which is sufficiently superheated, since this source of heat is much less harsh than the heat of a direct 25 fire, and is therefore less destructive to the lubricating properties of lubricating oils.

All which has been stated respecting petroleum oils, applies equally for all the other ethylenic, cyclic, hexano-cyclic hydrocarbons, as well for phenols, cresols, chlorobenzenes, nitro-benzenes (nitro-benzols), &c., 30 all of which are products that can be fractionated very properly by means of steam

and the use of vacuum, provided however 35 that the rectifier shall no longer be fed with the hydrocarbons in the liquid state as is generally done, but on the contrary shall be fed with hydrocarbons which have undergone preliminary vaporization, carried as far as possible, either by means of saturated 40 steam under high pressure, or by means of superheated steam.

The improved process is also applicable 45 to the extraction of benzene (benzol) from the heavy oils used for extracting benzene (benzol) vapour from coke oven gases.

What I claim is:—

Process for the continuous rectification of hydrocarbons and other liquids of high boiling point which comprises subjecting the 50 material to the indirect action of saturated steam whereby a portion of its constituents is vaporized, subjecting the residual unvaporized liquid material to the indirect action of superheated steam whereby the 55 same is mainly vaporized and bringing the vapours arising in both of the said treatments into intimate contact in a single rectifying column with a reflux of condensates 60 arising from said vapours and withdrawing the condensed material as a plurality of sharply defined fractions boiling within different temperature ranges.

In testimony whereof I have signed my name to this specification.

EMILE AUGUSTIN BARBET.
